Maurer & Co.

ATTORNEYS

UNITED STATES PATENT OFFICE.

ARTHUR C. GERBER, OF RENTON, WASHINGTON.

SWITCH.

Application filed December 26, 1923. Serial No. 682,779.

To all whom it may concern:

Be it known that I, ARTHUR C. GERBER, a citizen of the United States, and a resident of Renton, county of King, State of Washington, have invented a new and useful Switch, of which the following is a specification.

The present invention relates to improvements in switches, and has particular reference to a switch designed to be used in connection with a motor vehicle for the purpose of sounding the horn of the same. It is proposed to provide a switch of the character described that may be conveniently manipulated by the driver of the motor vehicle without necessitating his taking the hands off the steering wheel.

It is particularly proposed to provide as an operating element of the switch a wheel preferably of somewhat smaller dimensions than the steering wheel and disposed preferably on top of the same in concentric relation therewith, and to connect this operating wheel with the switch mechanism in such a manner that a contact is closed whenever any portion of the wheel is depressed by means of the thumb of the hand resting on the steering wheel. For this purpose a switch has been designed in which a contact is closed whenever a preferably disk-shaped element operatively connected with the wheel previously referred to is tilted at any point desired so that the switch may be actuated by the thumb of the hand resting on the steering wheel regardless of the position of the hand on the latter. Further objects and advantages of my device will appear as the specification proceeds.

The preferred form of my invention is illustrated in the accompanying drawing, in which Figure 1 shows my device attached to the top of the steering arrangement of a motor vehicle, Figure 2 a vertical section through my switch, Figure 3 a horizontal section taken along line 3-3 of Figure 2, and Figure 4 a horizontal section taken along line 4-4 of Figure 2. While I have shown only the preferred form of the invention, I wish to have it understood that various changes or modifications may be made within the scope of the claims hereto attached without departing from the spirit of the invention.

The tubular member (1), of which only the top is shown in Figure 2, may be considered to be any stationary portion of the steer-

ing wheel arrangement preferably extending above the steering wheel as shown in Figure 1. My switch mechanism comprising a cage (2) with an internal flange (3) at one end is shown as being partly inserted in the upper end of the tubular member (1) with a set screw (4) or any other suitable means holding the same in place.

The switch mechanism itself is fixed on a plug (6) adapted to be threaded into the cage (2) from the lower end and comprises in its principal features a disk (7) of insulating material having a plurality of contacts (8) secured therein, which latter contacts are preferably symmetrically grouped around the axis of the cage at a suitable distance therefrom. The contacts are interconnected by means of metal strips (9) so that the wire (10) directly connected to one of them as shown at (11) is in electrical connection with all of them.

Two crossing leaf springs (12) are secured to the upper face of the disk (7) in such a manner that the four arms of the two spring leaves extend over the four contacts (8) and are adapted to be forced into contact with the same when any one of the sliding members (13) mounted in the two plates (14) and (16) and normally forced upward by the springs (17) are depressed. The two spring leaves (12) are electrically connected with the wire (17') and the four plates, including the plug (6), the disk (7), the two plates (14) and (16), are united into one firm unit by means of small bolts (18) extending through the whole arrangement.

An insulating sheet (19) is provided on top of the plug (6), and insulating strips (21) are interposed between the spring leaves (12) and the sliding members (13) in the manner shown in the drawing. The plates (14) and (16), the disk (7) of insulating material and the plug (6) are held in spaced relation relative to one another by means of tubular spacing members (15) surrounding the bolts (18) and extending through the whole arrangement.

When the mechanism is introduced into the cage, it will be noted from Figure 2 that a space is left between the internal flange (3) of the cage and the top member of the switch mechanism and that the sliding members (13) extend into this space. On top of the sliding members is provided a disk (22) which rests loosely on the sliding members, the space provided for the

same being sufficiently large to allow of a limited amount of tilting motion. The disk has secured thereon the hub or central portion of the wheel (23), which latter is of considerably larger diameter than the cage (2) and is within reach of the thumb of the driver while the hand holds the steering wheel.

It will be readily seen that when any portion of the wheel (23) is depressed by means of the thumb, at least one of the sliding members (12) will be depressed, whereby two contact elements are forced into engagement and establish an electrical connection between the two wires (10) and (17'), which latter are part of a circuit operating a horn or any other alarm device.

The advantages of my device will readily appear from the foregoing description. The driver may firmly hold the steering wheel with both hands and sound the alarm by merely extending one of his thumbs and depressing a marginal portion of the wheel (23), whereby it makes no difference where his hand happens to be situated.

I claim:

1. A switch comprising a cylindrical cage having an internal flange at one end, a switch mechanism fixed to a plug adapted to be introduced from the other end having a plurality of interconnected stationary contact members grouped around the axis of the cage and an equal plurality of interconnected movable contact members grouped correspondingly, a plurality of sliding members adapted to force the movable contact members upon the stationary contact members extending outside of the mechanism and an element in-

terposed between the mechanism and the flange of the cage with limited freedom of tilting motion adapted to force two registering contacts into engagement when any marginal portion of the element is depressed.

2. A switch comprising a cylindrical cage having an internal flange at one end, a switch mechanism fixed to a plug adapted to be threaded into the other end of the cage having a plurality of interconnected stationary contact members grouped around the axis of the cage and an equal plurality of interconnected movable contact members grouped correspondingly, a plurality of sliding members adapted to force the movable contact members upon the stationary contact members extending outside of the mechanism and an element interposed between the mechanism and the flange of the cage with limited freedom of tilting motion adapted to force two registering contacts into engagement when any marginal portion of the element is depressed.

3. A switch comprising a cylindrical cage having an internal flange at one end, a switch mechanism fixed to a plug adapted to be threaded into the other end of the cage having sets of contacts grouped around the axis of the cage with sliding members extending outside the mechanism for operating a contact of each set, and an element interposed between the mechanism and the flange of the cage with limited freedom of tilting motion adapted to actuate a sliding member when any marginal portion of the element is depressed.

ARTHUR C. GERBER.
